RELAY SYSTEM

Edward M. Eadie, Jr., Westfield, N. J., assignor to Weston Electrical Instrument Corporation, Newark, N. J., a corporation of New Jersey

Application August 21, 1951, Serial No. 242,859

5 Claims. (Cl. 317—124)

This invention relates to relay systems and more particularly to a sensitive relay system that includes a sensitive measuring type instrument for the regulation of relatively heavy currents in control or alarm circuits.

Various types of relay systems have been proposed for controlling electrical equipment or alarm devices in accordance with minute variations in some measured quantity but such prior systems have been of comparatively complicated and expensive construction.

The present description will be restricted to an on-off light controller of the photocell-actuated type but the broad scope of the invention is not to be limited thereto as other appropriate uses of my system will readily be apparent to those skilled in this art.

In a photoelectric light controller of the type to which this invention relates, the varying outdoor illumination results in a varying current output of a photocell. Such photocell output controls the deflection of the movable contact arm of a sensitive instrument type relay provided with magnetic contacts. Closure of such relay contacts completes a circuit to an electric motor of the clock type whereby there is set into operation a mechanism that results in the closure or opening of heavy contacts for the control of the electric lights. Suitable arrangements are provided to prevent improper operation of the system and to bring the system to the at-rest position whereby no power is consumed until the next operation cycle is initiated.

An object of this invention is the provision of a control device including an instrument relay, magnetic elements for insuring a positive and reliable closure of the instrument contacts, and motor operated mechanism controlled by the instrument contacts for thereafter opening the contacts and controlling a switch or switches in the load circuit.

An object of this invention is the provision of a control device of the type stated in which a single instrument relay is employed to control both the on and off operation of the load switch and in which the motor operated mechanism includes elements for presetting the relay and for determining the operating sequence of the load switch.

An object of this invention is the provision of a control device including an instrument having a contact arm movable between two stationary contacts to close separate circuits therewith, magnetic elements for insuring a firm closure of the instrument contacts, a motor controlled by the closure of one or the other sets of instrument contacts, rotatable elements for actuation of a switch to the open or closed position and elements for opening the motor circuit after a predetermined time, and elements for resetting the instrument contacts before the opening of the motor circuit.

An object of this invention is the provision of a sensitive relay system for the regulation of relatively heavy current loads said system being of simple construction, positive operation and housed in a water-tight housing of the plug-in type.

These and other objects and advantages will become apparent from the following description when taken with the accompanying drawings. It is to be understood the drawings are for purposes of description and are not to be construed as defining the scope or limits of the invention, reference being had for the latter purpose to the appended claims.

In the drawings wherein like reference characters denote like parts in the several views:

Figure 1 is an isometric view of a control device made in accordance with this invention;

Figure 2 is a circuit diagram of the control device;

Figure 3 is a side elevation of the device shown in Figure 1;

Figure 4 is a front elevation of the device disposed within a circular housing of the outdoor, plug-in type; and

Figure 5 is a side elevation of Figure 4 with certain parts shown in section for the better illustration of the device.

Reference is now made to Figure 1 showing the assembly of the individual components upon a base 10 of insulating material. The sensitive relay 11 is of the permanent magnet, movable coil type that includes the movable coil 12 carrying an arm 13 movable over a graduated scale 14. The arm 13 carries a rider 15 of soft-iron that is arranged to contact one or the other of the stationary contacts 16, 17, that are supported in fixed position by suitable means. The contacts 16, 17 are small permanent-magnets. As is well known, rotation of the movable coil 12 will bring the rider 15 into the field of influence of one or the other of the stationary contacts. When this happens the rider is magnetically attracted to such contact resulting in a positive, firm contact closure. In magnetic contact relays of this type the energy developed by the instrument movable coil is, generally, not sufficient to separate the rider from the magnetic contact and, therefore, some mechanical contact-resetting means must be provided. Also, in an on-off controller, it is desirable to arrange the resetting mechanism such that the movable arm of the relay is free to contact only that stationary contact which will initiate the next desired operating cycle. For example, in a photoelectric light controller, if the relay arm 13 engages the stationary contact 16 the device will operate to cause a closure of a power switch to turn on the lights (indoor or outdoor). When that portion of the operating cycle is completed, the mechanical reset mechanism will separate the rider 15 from the contact 16 and will condition the relay for the next operating cycle, that is, closure of the contacts 15 and 17. Upon such latter contact closure the device will operate to open the power switch to turn the lights off after which the resetting mechanism will separate the rider 15 from the contact 17 and condition the relay for the next operating cycle, namely, a subsequent closure of the contacts 15 and 16. A complete operating cycle of the device will be described in detail hereinbelow. It is here pointed out that the movable coil 12 of the relay is electrically connected to the terminals 20, 21, the stationary, magnetic contacts 16 and 17 are connected to the terminals 22, 23, respectively, and the movable arm 13 is connected to the terminal 24.

The sensitive relay 11 is mounted on the front of the base 10 by the four screws 25. It may here be stated the cover of the relay is made of a transparent plastic affording a ready view of the internal parts, particularly the arm 13, contacts 16 and 17 and the scale 14. Attached to one side of the relay cover is a bracket 27 supporting the rod 28 that has one end extending through a clearance hole in the plate 29. A freely-rotatable sleeve 30 is disposed between the rear arm of the bracket 27 and the front face of the plate 29, and the rod 28 has an enlarged head contacting the rear of the plate 29, from which it will be apparent the rod 28 forms an axis about which the plate 29 can be rotated. A hollow rod 31 is rigidly secured to the plate 29. This rod accommodates the end of a smaller, solid rod 32 having a right angle bend therein, said rod 32 passing into the relay 11 through a bushing 33 secured to the side of the relay cover, substantially as shown. The inner end of the rod 32, that is, the end disposed within the relay, lies in a plane above that in which the relay arm 13 rotates and such inner end carries a bushing 34 to which a thin, curved wire 35 is attached, as by soldering or welding. This wire 35 has a central portion passing over the relay arm and the ends of the wire are offset downwardly (toward the base of the relay). Ceramic bushings 36, 37 are carried, individually, by the ends of the flexible wire 35. The spacing between the bushings 36, 37 is such that when the reset rod 32 is in the position shown the bushing 36 prevents the relay arm 13 from contacting the stationary contact

16 while the bushing 37 lies out of the path of travel of the arm in the direction of the stationary contact 17. Assuming now that the relay arm 13 has contacted the stationary contact 17, it will be apparent those contacts will be separated when the reset arm 32 is moved further into the relay housing. Such movement of the reset arm will cause the ceramic bushing 37 to move the arm 13 toward the center of the scale 14 and out of the field of influence of the magnetic contact 17. In so resetting the contacts 15 and 17 the other ceramic bushing is moved to a point out of the path of travel of the relay arm when the arm moves in the direction of the other stationary contact 16. Consequently, in the operation of the resetting mechanism, the relay 11 is conditioned such that the movable arm can only engage the proper stationary contact to initiate the next desired operating cycle of the device as a whole. Since the plate 29 is pivotally movable about the axis formed by the rod 28, it is apparent that a counter-clockwise rotation of the plate will cause the reset arm to move further into the relay housing, bringing about the condition just described. A subsequent clockwise rotation of the plate 29 will restore the reset arm, and the ceramic bushings 36, 37 to the position shown in Figure 1.

Rocking movement of the plate 29 is controlled by a bracket 40 that is pivotally secured to the base 10 by means of a large headed screw 41. The bracket 40 has an offset, upper portion to which a pair of conventional spring clips 42 are attached, as by the rivets 43, said spring clips serving as supports for a mercury switch 44 that is connected by the flexible leads 45 to terminals 46 secured to the base 10 by screws 46'. The terminals 47 are likewise secured to the base 10 and serve as a means for connecting the mercury switch into an electrical circuit. It will be noted that the bracket 40 includes an extended, tapered end 50 that extends under the pivoted plate 29. A rod 51 passes through an opening in the tapered end 50 such rod being secured rigidly to the end 50 as by soldering. One end of the rod 51 passes through a slot 52 in the plate 29 while the other end passes through an opening 51 in the base 10 and occupies a position between the offset ends of a switch comprising the blades 55, 56. The switch blades 55, 56 are mounted on the rear of the base 10 as will be explained in detail with reference to Figure 3, below. When the bracket 40 is rotated in a clockwise direction, about its mounting screw 41, the rod 51 will impart a counter-clockwise rotation to the pivoted plate 29 thereby moving the reset rod 32 further into the housing of the relay 11 and separating the relay contacts 15, 17. A subsequent counter-clockwise rotation of the bracket 40 will return the plate 29 and the reset rod to the position shown in the drawing. Thus, the opening and closing of the mercury switch is mechanically tied-in with the resetting of the relay contacts in a simple and positive manner.

The rocking movement of the bracket 40, carrying the mercury switch, is controlled by rotation of the relatively thick disc 60 that is eccentrically, but rigidly, attached to the shaft 61 extending from the gear box 62 of a small, clock-type motor 63. The disc 60 extends through a clearance opening 64 in the base 10 and its diameter is such that the disc just fits between the downwardly-depending arms 65 that are an integral part of the bracket 40. Since the bracket 40 is pivoted at a point spaced from the disc 60, specifically, by the screw 41, rotation of the disc will impart a rocking movement to the bracket. Consequently, by de-energizing the motor at the proper points in the operating cycle, the bracket 40 will occupy two positions. One such position is shown in Figure 1; the mercury switch contacts being closed in this position. The other position is such that the mercury switch is tilted approximately 30 degrees, in a counter-clockwise direction from the Figure 1 showing, and in which position the mercury switch contacts are open-circuited.

De-energization of the clock motor is accomplished by the switch blades 55, 56 that are mounted on the back of the base 10, as shown more clearly in the side elevation view, Figure 3. The blades are electrically insulated from each other and the mounting bracket 70 by conventional spacers 71, the entire complement of blades and spacers being held together by two screws 72 (only one such screw being visible in Figure 3) that pass through insulator tubes disposed in aligned openings in the blades and spacers, as is well known in this art. Two screws 73 (only one such screw being visible in Figure 3) secure the angle bracket 70 to the base 10 and position the two blades

properly with respect to the rod 51, see Figure 1. Each blade carries a contact button 55' and 56' and the blades are so assembled that the contact buttons normally engage each other, that is, the electrical circuit between the two blades is closed when the rod 51 occupies a position intermediate of the offset ends of the blades. Since the rod 51 moves with the bracket 40 it will be apparent the rod will flex the blade 56 when the bracket 40 rotates a predetermined amount in the counter-clockwise direction thereby separating the contact buttons 55', 56'. Likewise, upon a predetermined amount of clockwise rotation of the bracket 40 the rod 51 will flex the blade 55 and so also separate the contact buttons 55', 56'. By connecting the blades 55, 56 between the clock motor and the source of power it will be apparent the motor will be de-energized when the rod 51 causes a separation of the contact buttons 55', 56'. Although the motor shaft 61 rotates in only one direction the eccentrically-mounted disc 60 imparts a rocking movement to the mercury-switch-carrying bracket 40 and the limits of such rocking motion are established by the opening of the contact buttons 55', 56'.

A photoelectric cell 75, preferably of the dry disc, self-generating type is disposed in front of the sensitive relay being supported from the base 10 by a suitable bracket 76. The photoelectric cell is connected to the movable coil of the relay by leads soldered to the relay terminals 20, 21 whereby the relay arm 13, or pointer, takes up a position, relative to the scale 14, depending upon the amount of light striking the photocell surface. As shown in Figure 3, the photoelectric cell can be tilted to a limited extent in order to respond to light coming predominantly from a desired direction. Any suitable mounting may be employed for the adjustable support of the photoelectric cell.

With further reference to Figure 3, it will be noted the base 10, upon which the components of my control device are mounted, is supported on a metal sub-base 80 by the posts 81 that are attached to the sub-base as by peening over the post ends. The mounting screws 82 pass through holes 83 in the base 10 (see Figure 1) and are threaded into the posts. Such mounting of the base 10 on a sub base is desirable when the entire control apparatus is encased in an outdoor housing of the plug-in type, as the entire apparatus can be removed from the front of the housing by unscrewing the mounting screws 82. The housing will be further described hereinbelow with reference to Figures 4 and 5.

Reference is now made to Figure 2 which is a wiring diagram of the light controller and includes a diagrammatic representation of the various components and their functions. The photocell 75 is connected directly to the movable coil 12 of the sensitive relay 11 by the leads 85. Conventional hair springs normally bias the movable coil so that the arm 13 moves to a point beyond the stationary contact 16 when no current flows through the movable coil. In other words, the movable coil and its arm 13 rotate in a clockwise direction with increasing current flow through the coil. Those skilled in this art will know that the photocell-relay combination can be adjusted so that contact closure between the rider 15 and either of the magnetic contacts 16, 17 will take place when the light intensity on the photocell surface drops or increases to predetermined values. As shown in the drawing the apparatus is in the "at rest" position and the mercury switch 44 is in the closed circuit position. Consequently, the lamps 86, which may be room lights, street lights or etc., are "on" being energized by the power source connected to the terminals 87. The terminals 87 are carried by the base 10 of the controller, as shown in Figure 1. As explained above, when the mercury switch is in the closed position the reset arm 32 of the relay occupies a position whereby the ceramic bushing 36 prevents closure of the rider 15 with the contact 16. Thus, a decrease in the amount of light striking the photocell surface merely results in the relay arm 13 striking the bushing 36 but the controller remains in the "at rest" position. As the light intensity increases the movable coil 12 and arm 13 rotate in a clockwise direction and closure of the relay contacts 15 and 17 occurs when the light intensity reaches a predetermined magnitude. Closure of the contacts 15, 17 energizes the clock motor 63, the circuit comprising the wires 90, 91, 92, contacts 15, 17, wires 93, 94, 95, the motor 63, and wires 96, 97. Rotation of the motor shaft 61 results in a corresponding rotation of the disc 60. Referring

now to Figure 1, rotation of the disc 60 imparts a clockwise rotation to the bracket 40 whereby the mercury switch 44 tilts toward the open circuit position, the rod 51 moves away from the lower switch blade 56 permitting closure of the contact buttons 55', 56', and the pivoted plate 29 moves in a counter-clockwise direction. The various cooperating parts are so designed that the stated operations occur in the following order:

1. The contact buttons 55', 56' close. As shown in Figure 2, those contacts are connected in parallel with the relay contacts and in series with the clock motor. Thus, the motor will continue to run as long as these contacts are closed.

2. The pivoted plate 29 (Figure 1) causes the reset rod 32 to move further into the relay. Such movement of the rod causes the ceramic bushing 37 to force the relay contact 15 away from the contact 17. However, since such separation of the relay contacts takes place after the contact buttons 55', 56' have closed, the motor continues to run even though the relay contacts are opened. When the limit of travel of the reset rod is reached the ceramic bushing 37 will prevent further contact between the rider 15 and the contact 17, and the other bushing 36 will be removed from the path of the pointer travel toward the contact 16.

3. The mercury switch tilts to the open circuit position and the lamps 86 go "out."

4. The rod 51 flexes the upper contact blade 55 thereby separating the contact buttons 55', 56'. Since the relay contacts 15, 17 have already been opened by the reset rod 32, separation of the contact buttons 55', 56' de-energizes the clock motor.

It is apparent that upon completion of the above cycle of operation all components are "at rest" and energy is not consumed from the 110 volt power source. When the light striking the photocell surfaces decreases, as at dusk, the relay arm will move toward the stationary contact 16, eventually closing therewith when the light intensity drops to the predetermined value. Closure of the relay contacts 15, 16 energizes the clock motor, the circuit comprising the wires 90, 91, 92, contacts 15, 16, wires 98, 99, 95, motor 63, and wires 96, 97. Rotation of the disc 60 now imparts a counter-clockwise movement to the bracket 40 whereby the above-listed operations again take place in the order stated. Now, however, the mercury switch 44 tilts to the closed circuit position closing the power circuit to the lamps 86, the reset rod 32 separates the relay contacts 15, 16 and conditions the relay for a subsequent closure of the contacts 15, 17, and the rod 51 eventually flexes the contact blade 56 to open the motor-control contact buttons 55', 56'.

By mechanically linking together the movement of the mercury switch, the resetting of the sensitive relay contacts, and the operation of the motor-control contact buttons, proper operation of the controller is assured. Once the relay contacts close the motor is energized and a re-opening of the relay contacts takes place only after the contact buttons 55', 56' are closed. Consequently, the relay contacts are opened, under a condition of no load, thereby promoting long contact life. Since the opening of the contact buttons 55', 56' is controlled by the rod 51 attached to the rocking bracket 40 it is apparent that the extremity of oscillation of the bracket is determined by the positioning of the contact blades 55, 56 relative to the rod 51. These blades are so positioned that the motor is de-energized at a point just prior to the extreme limit of rotation, in either direction, imparted to the bracket 40 by the disc 60. As is well known, the mercury switch opens and closes in response to a relatively small angular tilting thereof. In the design of the apparatus the bracket 40 is subject to an angular rotation that exceeds the necessary angular tilting of the mercury switch thereby providing an ample safety factor to assure on-off operation of the external load within the two operating cycles described above. Inasmuch as the movable parts are subject to limited movement at relatively slow velocity, the factor of wear is insignificant resulting in a device having a long operating life with minimum maintenance.

Photoelectric light controllers are used quite extensively to control street lights and it is desirable to mount the controller on the light stanchion or pole. To facilitate such mounting of the controller I place the entire device within a glass front, plug-in housing of the type commonly employed to house watt-hour meters, as shown

5 in Figures 4 and 5. The housing comprises a base 90 carrying the blade-type terminals 91, each terminal being insulated from the base by a suitable insulator member 92. The outer ends of the terminals are adapted to plug into cooperating spring-type contacts carried by a socket member that is secured in fixed position, said spring type contacts being connected to appropriate electrical circuits. The device carried by the base 90 is adapted for mechanical and electrical connection and dis-connection with the socket member through the cooperating terminals carried by the base 90 and the spring contacts carried by the socket member.

15 A glass cover 93 is attached to the base 90 by a ring member 94, said ring member being of the type that causes the base 95 of the glass cover, to compress the gasket 96 against the lip 97, of the base, to provide a water tight joint. As already described, the components of the light controller are mounted upon an insulator base 10 that is, in turn, supported on a sub-base 80 by the posts 81 and screws 82. This sub-base 80 is supported in spaced relation relative to the base 90, of the housing, by a set of studs 99 and 100, the latter being threaded to accommodate the screw 101.

20 All necessary electrical connections between the components of the controller are made to the terminals 87 and 46, carried by the base 10. Electrical connections between the terminals 87, 46 and the blade-type terminals 91, carried by the housing base 90, are made by suitable, flexible cables 102 passing over the top and bottom edges of the base 10, said cables being provided with solder terminals for this purpose. Thus, the plugging-in of the terminals 91 into the cooperating spring contacts of the socket member places the controller in operating condition. The glass cover exposes the entire device to ready view. In the event of failure of any component, or damage thereto, a new controller can be substituted, in situ. The glass cover of the housing is removable from the base 90 upon rotating the cover and ring 94 approximately 20 degrees. The connection cables are disconnected from the main base 10 and the entire assembly removed by unscrewing the mounting screws 82 by which such base is attached to the supporting posts 81.

25 Having now described my invention in detail in accordance with the patent statutes, certain changes and modifications in the arrangement of the parts will be apparent to those skilled in this art. Such changes and modifications may be made without departing from the scope and spirit of the invention as set forth in the following claims.

I claim:

1. Control apparatus comprising a sensitive relay having a pivotally-mounted movable coil carrying a contact arm and stationary contacts disposed on opposite sides of the contact arm, said contact arm engaging one or the other of the stationary contacts in accordance with the magnitude of the current flowing in the movable coil; a reset member movable in one direction to move the relay contact arm out of engagement with one stationary contact and movable in the reverse direction to move the contact arm out of engagement with the other stationary contact; a uni-directional motor having a shaft; circuit elements connecting the motor to a source of electrical energy upon closure of the relay contact arm with either of the stationary contacts; a disc eccentrically secured to the shaft; a pivotally-mounted bracket having a pair of spaced arms extending along diametrically opposed sides of the disc, said arms being contacted by the peripheral surface of the disc, upon eccentric rotation of the latter, to thereby impart oscillatory rotation to the bracket; a mercury switch carried by the bracket, said switch being closed upon rotation of the bracket in one direction and opened upon bracket rotation in the other direction; mechanical coupling means between the bracket and reset member to move the reset member in one direction or the other in correspondence with the rotary movement of the bracket; a normally-closed holding switch comprising contacts carried by a pair of flexible blades, one blade being connected to the relay contact arm and the other being connected to both said stationary contacts; and means carried by the bracket and opening the holding switch contacts at points just prior to the limits of the rotary movement of the bracket.

2. The invention as recited in claim 1, wherein the

said mechanical coupling comprises a pivotally-mounted plate rotatable in a plane substantially parallel to the plane of movement of the reset member, said plate including a slot and carrying a hollow rod, an offset end on the reset member, said end being loosely disposed in the said hollow rod, and a pin secured to the bracket and extending through the said slot.

3. The invention as recited in claim 2, wherein the said pin also constitutes the means opening the said holding switch contacts.

4. A photoelectric controller comprising a mounting plate; a sensitive relay having a pivotally-mounted movable coil carrying a contact arm and stationary contacts disposed on opposite sides of the contact arm, said contact arm engaging one or the other of the stationary contacts in accordance with the magnitude of the current flowing in the movable coil; a photoelectric cell carried by the mounting plate and connected to the relay movable coil; a pusher rod extending externally of the relay housing and having an offset outer end; a pair of flexible members secured to the inner end of pusher rod, said members lying in the path of travel of the relay contact arm and being spaced apart a distance less than the spacing between the stationary relay contacts; a coupling plate having a slot and carrying a tube within which is disposed the offset end of the pusher arm, said plate being pivotally secured to the exterior of the relay housing and rotatable in a plane substantially parallel to the plane of movement of the relay contact arm; a uni-directional motor carried by the mounting plate and having a shaft; circuit elements connecting the motor to a source of electrical energy upon closure of the relay contact arm with either of the stationary contacts; a disc eccentrically secured to the motor shaft; a bracket pivotally secured to the mounting plate and rotatable

5 in the plane of said coupling plate, said bracket having a pair of spaced arms extending along and adjacent to diametrically-opposed sides of the disc such that the arms are contacted by the peripheral surface of the disc upon eccentric rotation of the latter to thereby impart oscillatory rotation to the bracket; a mercury switch carried by the bracket, said switch being opened and closed respectively upon rotation of the bracket in one or the other direction; a pin carried by the bracket and extending through the slot in the said coupling plate; a pair of flexible blades carried by the mounting plate and having ends spaced on opposite sides of the said pin; normally-closed cooperating electrical contacts carried by the blades; and leads connecting one blade to the 10 relay contact arm and the other blade to both stationary contacts of the relay, the said pin flexing one or the other of the spaced ends of the flexible blades to separate the said cooperating contacts when the bracket approaches its limit of oscillatory movement.

5. The invention as recited in claim 4, wherein the stationary relay contacts are permanent magnets and the relay contact arm carries a rider of magnetic material for engagement with the stationary contacts.
